UNITED STATES PATENT OFFICE

172,947

ADVERTISING DISPLAY

Ray Becker, Cincinnati, Ohio, assignor to The Ohio Advertising Display Company, Cincinnati, Ohio, a corporation of Ohio

Application October 19, 1953, Serial No. 27,212

Term of patent 3½ years

(Cl. D1—12)

To all whom it may concern:

Be it known that I, Ray Becker, a citizen of the United States, residing at Cincinnati, in the county of Hamilton and State of Ohio, have invented a new, original, and ornamental Design for an Advertising Display, of which the following is a specification, reference being had to the accompanying drawings, forming a part thereof.

I claim:

The ornamental design for an advertising display, substantially as shown.
